UNITED STATES PATENT OFFICE

WILLIAM H. HOUGHTON, OF LOS ANGELES, CALIFORNIA

BUILDING CONSTRUCTION

Application filed March 20, 1929. Serial No. 348,466.

My invention is in a building construction and may be considered as a further development of that set forth in my Patent No. 1,491,404, dated April 22, 1924.

5 An object of my invention is a building construction in which the wall sections are built up of interlocking panels and blocks preferably formed of cement or concrete in such a manner that I may have a filling of 10 concrete on the outer part of the wall and a hollow inner wall. In this connection the panels of the concrete filled wall are preferably formed with dovetail grooves thus giving a bond for the concrete filling.

15 Another object of my invention is in constructing a ceiling or floor construction by means of interlocking slabs of cement with interlocking blocks at the juncture of certain slabs whereby on filling the space between 20 lower and upper slabs and utilizing metal reinforcing, a floor is formed in which the floor surface is formed of concrete slabs and the ceiling below also of concrete slabs. The slabs where I have the concrete filling between 25 are also preferably dovetailed on their inner faces.

In regard to my detail construction a further object of my invention in the wall construction is having the concrete panels spaced by vertical filler blocks and having the inside wall which is hollow spaced by horizontal interlocking blocks. These blocks are preferably arranged so that they break joint and thus form a strong wall when the outer 30 wall has a concrete filling, and is provided with metal reinforcing bars embedded therein and passing through a notch in the blocks.

My invention is illustrated in the accompanying drawings, in which:

40 Fig. 1 is a perspective view of a wall construction partly broken away, showing a section through a floor and ceiling construction,

Fig. 2 may be regarded as a vertical section on the line 2—2 of Fig. 1 in the direction 45 of the arrows, showing the outer wall extended upwardly and illustrating a ground floor construction,

Fig. 3 is a detail horizontal section substantially on the line 3—3 of Figs. 1 or 2 in 50 the direction of the arrows,

Fig. 4 is a plan of one of the horizontal filler blocks as if taken in the direction of the arrow 4 of Fig. 1 of the block alone,

Fig. 5 is a side elevation of such a block taken in the direction of the arrow 5 of Fig. 4,

Fig. 6 is an end elevation taken in the direction of the arrow 6 of Fig. 5,

Fig. 7 is an inside elevation of one of the wall panels, or it may be considered as an inside view of one of the floor or ceiling slabs,

Fig. 8 is a section on the line 8—8 of Fig. 7 in the direction of the arrows,

The wall construction is substantially as follows, and embodies an outer wall 11 which is formed of panels and blocks filled with concrete. Inside of this there is an inner wall 12 which is formed of panels and interlocking blocks, but no concrete filling, leaving dead air spaces. In constructing the outside wall I utilize panels 13 which are substantially rectangular and have dovetail grooves 14 on their inside surface, these grooves preferably extending lengthwise of each of the panels. The panels at one edge have an inwardly extending groove 15 formed by a front projecting tongue 16 and a middle projecting tongue 17. The marginal surface 18 from the tongue 17 slopes inwardly. At the opposite edge there is a middle tongue 19 and an inner tongue 20 forming a groove 21 at the back 80 and the sloping surface 22 at the edge. By this construction the edges of adjacent panels interlock as indicated in Fig. 3.

The upper and lower surfaces are also made with a similar construction. The upper edge 85 indicated at 23 has the two tongues with the groove between, but in this case the inner tongue and inner groove are intersected by the dovetail grooves. Thus the panels when placed together interlock on both sides at the 90 top and at the bottom.

The outer walls have a series of blocks 24 which extend between the inner and outer panels, these being indicated in Fig. 1. They are provided with double tongues 25 on the marginal edges and double tongues 26 on the top and bottom edges. They have flat vertical sides 27 and flat tops 28. Therefore, these blocks may be caused to interfit with the 95 panel pieces on the top of the panels as indicated in Fig. 4.

cated at 29 and also underneath the panels as indicated at 30. (See Fig. 1.)

Reinforcing bars 31 extend horizontally between the front inside and outside panels of the outer wall 11 and through the vertical blocks 24. There are also vertical reinforcing bars 32 extending upwardly between the vertical blocks 24; and between the inner and outer panels of the outside wall there is preferably a filling of concrete 33.

The inner wall 12 utilizes the inner series of panels of the outside wall so that the whole wall may be considered as formed of an outer face 34 formed of panels and the outer surfaces of the vertical blocks 24. A middle section 35 is formed of panels and the inner face of the blocks 24. As above mentioned, the outer face 34 and the middle section 35 with the concrete filling form the outer wall 11.

The inner face 36 is formed of panels 37 preferably rectangular, but these are constructed without a dovetail on the inner construction. They are provided with double tongues and grooves on the side edges 38 and also with double tongues and grooves on the top and bottom edges 39. These double tongues and grooves are made in the same manner as on the panels for the outer wall. The horizontal blocks 40 are also substantially similar in shape to the blocks 24 and are illustrated in detail in Figs. 4, 5 and 6, and bear the same numerals as identify the features of the vertical blocks 24. These blocks are preferably installed to break joint so that the panels can be made of different lengths as indicated in Fig. 2.

The floor and ceiling construction connects to the inner wall by means of special blocks 41 illustrated in section in Figs. 1 and 2. These have double tongues and grooves 42 on the outer face and also double tongues with a single groove 43 extending partly inwardly. There is an inwardly extending tongue 44 which fits between an upper slab 45 of a floor construction and a lower slab 46 forming a ceiling construction. Each of these slabs is dovetailed on the inner surface as indicated at 47. The floor slabs are of the same general type of construction as the wall panels having the dovetail backs, and are provided with the double tongues 48 and 49 on all their edges, these tongues being positioned in a reverse direction so that the slabs will interlock.

In the floor construction I also incorporate concrete blocks 50 which are of the same general character as the vertical blocks 24 of the outer wall and the horizontal blocks 40 of the inner wall. These blocks have double tongues 51 (note Figs. 1 and 2) interlocking with the floor slabs. The blocks may be placed continuously end to end forming in effect a beam structure or may break joint with the slabs if desired, the side edges at the top and bottom and the end edges also

at the top and bottom being formed to interlock with the slabs. In the floor construction there are notches 52 in the blocks 50 and notches 53 in the special blocks 41 and through these notches there are fitted reinforcing bars 54 which have their ends bent at an angle as indicated at 55 in the outside wall. A filling of concrete 56 fills the space between the notch and floor slabs and embeds the reinforcing bars 54. This cement or cement grout fills the notches in the blocks. It will be noted that the vertical blocks 24 have notches 57 in which the reinforcing bars 31 are embedded.

It is more or less immaterial as to the manner in which the wall is built up from the foundation, but for convenience of assembly I utilize special floor slabs 58 (note Fig. 2). These slabs are provided with a plurality of inner grooves 59, a center 60 and grooves 61 and 62 parallel to the center. The floor slabs are supported on foundation blocks 63 and 64 or other suitable construction. These grooves in the floor slab allow the lower edges of the wall panels to fit therein and in such manner interlock. The concrete filling of the outer wall fills in the center 60 and firmly locks the panels on the outer and middle part of the outer wall together.

It is obvious that the same general type of construction, using middle panels and the similar type of construction for floor and ceiling slabs, allows economy to be exercised in the manufacture of such panels and slabs, and these may also be incorporated in roof constructions, either flat or sloping roofs, as the desire may be. The blocks fitted in the outside and inside portions of the walls and in the floors may be of substantially the same type, and in some cases may be made to the same dimensions, thus also affording economy in manufacture. It will be apparent that the elements of my wall are readily assembled and that no mold or forms are required.

Various changes may be made in the principles of my invention without departing from the spirit thereof, as set forth in the description, drawings and claims.

I claim:

1. A building construction having a wall with three distinct and separate vertical structures formed with an outer panel structure, an inner panel structure, and a central panel structure, there being blocks connecting between the outer and the center structures and terminating at said structures and additional blocks between the inner and center structures and terminating at said structures, thereby providing spaces between the blocks, and a composition filling between the outer and center panel structures.

2. A building construction having a wall with three distinct and separate vertical structures formed with an outer panel structure, an inner panel structure, and a center

panel structure, all spaced apart, blocks between the outer and the center structures terminating at said structures and additional blocks between the inner and central structures terminating at said structures, the outer and the central panel structures having dovetails facing one another, and a composition filling between the outer and the center structures engaging the said dovetails.

10 3. A building construction having a wall with three distinct and separate vertical structures with an outer panel structure, an inner panel structure, and a center panel structure, each being formed of individual 15 panels, a series of blocks engaging and spacing the panels of the outer and center structures, a separate series of blocks engaging the panels of the inner and center structures and terminating at said structures, the said 20 panels and blocks having interlocking tongues and grooves, and a composition filling between the outer and the center panel structures.

4. A building construction having a wall 25 with three distinct and separate vertical structures with an outer panel structure, an inner panel structure, and a center panel structure, each formed of individual panels, vertical spacing blocks between the outer and 30 the center panel structures terminating at said structures, separate spacing blocks between the inner and central panel structures terminating at said structures, the said panel structures and the blocks having interlocking 35 double tongues and grooves, each of the tongues having a sloping surface and a surface substantially parallel to the planes of the panel, the said panels and blocks interfitting at the tongues and grooves, and a composition 40 filling between the outer and the center panel structures.

5. A building construction having a wall 45 with three distinct and separate vertical structures with an outer panel structure, an inner panel structure, and a center panel structure, each formed of a number of individual panels, spacing blocks between the outer and center structures terminating at said structures, additional spacing blocks between the inner and center structures terminating at said structures, the said panels and blocks having double tongues and grooves to interlock, the tongues having sloping surfaces and each with an adjoining surface parallel to the plane of the panels, the outer and center panel structures having dovetailed grooves, and a composition filling in said 55 grooves and between the outer and center panel structures.

60 6. A building construction having in combination a wall with three distinct and separate vertical structures formed with an outer panel structure, an inner panel structure, and a center panel structure, spacing blocks between the inner and center panel structures,

a flooring and ceiling construction having an upper and a lower panel structure with spacing blocks between said structures, and certain of the spacing blocks of the wall also forming spacing blocks for the floor and 70 ceiling.

7. A building construction comprising in combination a wall with three distinct and separate vertical structures having an outer, inner and a center panel structure, each 75 formed of individual panels placed edge to edge, vertical spacing blocks between the outer and the center structures only, and horizontal spacing blocks between the inner and center structures terminating at said structures, a floor and ceiling construction having an upper and lower panel structure formed of individual panels with spacing blocks between said latter panels, a row of the horizontal blocks in the wall forming spacing 80 blocks for the flooring and ceiling construction, the said panels and the spacing blocks having double tongues, the said tongues having substantially parallel sloping surfaces providing interlocking joints between the individual panels and the individual blocks.

In testimony whereof I have signed my name to this specification.

WILLIAM H. HOUGHTON.
